UNITED STATES PATENT OFFICE.

CARL H. HOFFSTETTER, OF ERIE, PENNSYLVANIA, ASSIGNOR TO ODIN STOVE MANUFACTURING COMPANY, OF ERIE, PENNSYLVANIA, A CORPORATION OF PENNSYLVANIA.

STOVE.

Application filed July 1, 1921. Serial No. 481,796.

To all whom it may concern:

Be it known that I, CARL H. HOFFSTETTER, a citizen of the United States, residing at Erie, in the county of Erie and State of

5 Pennsylvania, have invented new and useful Improvements in Stoves, of which the following is a specification.

With stoves such as receive their supply of gas at the end of the burner and particularly stoves which use a radiant to which flame is delivered it is difficult to so introduce the gas as to get a uniform flow from each group of jets. One of the purposes of this invention is to obviate this 15 difficulty.

The invention is illustrated in the accompanying drawing as follows:—

Fig. 1 shows a front view of the stove, partly in section, on the line 1—1 in Fig. 2.

20 Fig. 2 a section on the line 2—2 in Fig. 1.

Fig. 3 a section on the line 3—3 in Fig. 1.

Fig. 4 a section on the line 4—4 in Fig. 1.

1 marks the base of the stove, 2 the sides and 3 the back on the stove. A burner 4 has the lugs 4^a which extend to the back 3 and the burner is secured by screws 5 extending into the lugs 4^a. The inlet end of the burner is provided with a mixer 6 and a supply valve 7 in the usual manner.

30 The burner has the burner chamber 8 from which lead the jet openings 9. These are formed with stools extending upwardly from the upper wall of the burner. Thimbles 10 are arranged over the stools 9 and these are provided with burner gauze tops 11 making in effect a group of jets extending from the top of the thimble. Tubular radiants 12 of heat-resisting material, scroll-formed, are arranged over the jet 40 groups and extend upwardly above the burner.

The burner has a depression 13 at its inlet end above which there is formed a baffle 14 extending from the inlet end and 45 preferably inclined toward the center. An upturned passage 15 extends from the depression 13 and a baffle 16 is arranged directly over the upturned passage 15.

With this construction the incoming gas is in effect delivered at the center, is deflected equally in both directions and thus feeds the groups of jets equally. The baffle 16 prevents a direct flow of the gas to the jets immediately above it.

In order to prevent the ready displacement of the radiants 12 a lip 4^a may be provided along the burner in front of said radiants.

I form a simple backing 17 for the radiants by utilizing an asbestos board, bending the edges as shown at the ends and arranging the edges along the plates 18 forming deflecting sides of the stove front. In this way the board not only forms a backing but also protects the sides from the immediate action of the incandescent radiants. The board is spaced from the metal back 3 so as to insulate this back from the heat of the radiants.

What I claim as new is:—

1. A burner having a burner chamber, the chamber having a mixture inlet passage at one end extending from the burner and in alinement therewith; and a baffle over the inlet end extending into the chamber forming an upturned passage intermediate the ends of the chamber.

2. A burner having a burner chamber, the chamber having an inlet passage at one end; and a baffle over the inlet end extending into the chamber forming an upturned passage intermediate the ends of the chamber, said baffle having a downward inclination toward the center.

3. A burner having a burner chamber, the chamber having a depression at one end in extension of a mixture inlet passage; and a baffle extending from the inlet end over the depression forming an upturned passage intermediate the ends.

4. A burner having a burner chamber, the chamber having a depression at one end in extension of a mixture inlet passage; a baffle extending from the inlet end over the depression forming an upturned passage intermediate the ends; and a baffle over the upturned passage.

5. A burner having a burner chamber, the chamber having a mixture inlet passage at one end extending from the burner and in alinement therewith, and a baffle over the inlet end extending into the chamber forming an upturned passage at the center of the burner delivering mixture equally to the ends of the burner.

In testimony whereof I have hereunto set my hand.

CARL H. HOFFSTETTER.
